(57) **CLAIM**

We claim, the ornamental design for a cradle for a medical cooling device, as shown and described.

DESCRIPTION

FIG. 1 is a perspective view of a cradle for a medical cooling device according to the new design.

FIG. 2 is a front view of the cradle for the medical cooling device of FIG. 1.

FIG. 3 is a rear view of the cradle for the medical cooling device of FIG. 1.

FIG. 4 is a left side view of the cradle for the medical cooling device of FIG. 1.

FIG. 5 is a right side view of the cradle for the medical cooling device of FIG. 1.

FIG. 6 is a top plan view of the cradle for the medical cooling device of FIG. 1; and,

FIG. 7 is a bottom plan view of the cradle for the medical cooling device of FIG. 1.

The broken lines shown in FIG. 6 illustrate portions of the cradle for the medical cooling device that form no part of the claimed design.
